UNITED STATES PATENT OFFICE.

CHARLES SIMEK, OF CHICAGO, ILLINOIS, ASSIGNOR TO THE GARFORD MANUFACTURING COMPANY, OF ELYRIA, OHIO, A CORPORATION OF OHIO.

AUTOMOBILE-HORN.

1,318,613.

Specification of Letters Patent.

Patented Oct. 14, 1919.

Application filed March 22, 1916. Serial No. 85,756.

To all whom it may concern:

Be it known that I, CHARLES SIMEK, a citizen of the United States, and a resident of Chicago, in the county of Cook and State 5 of Illinois, have invented certain new and useful Improvements in Automobile-Horns; and I do hereby declare the following to be a full, clear, and exact description of the invention, such as will enable others skilled in 10 the art to which it appertains to make and use the same.

My invention relates to automobile horns, and more particularly to the type of automobile horns known as hand horns to distinguish them from electric horns. Horns 15 of this type are operated mechanically by applying pressure directly to some portion of the horn, through the hand or foot of the driver.

20 I am aware that horns of this type were made and used prior to my invention, but for the most part they are complicated, expensive and troublesome to make.

Among the objects of my invention I aim 25 to simplify devices of the character which I have mentioned by eliminating many of the parts which have been used, thereby producing a horn which is cheap and easy to make, and which, at the same time, will 30 produce a loud signal when operated.

Other objects of my invention and the invention itself will probably be better understood from a description of an embodiment of the invention.

35 Figure 1 is a sectional view through an embodiment of my invention, showing the mechanical means employed for operating the horn. This view is taken on the line I—I of Fig. 2.

40 Fig. 2 is a section taken through the line II—II of Fig. 1 showing a front elevation of the mechanism.

Fig. 3 is an enlarged view of some of the details.

45 Referring now to the drawing and to the embodiment of my invention illustrated therein, at 4 is shown a frame which here includes a cup-shaped casing, preferably cylindrical in form and provided with a 50 bottom 5. This casing may, as shown, be punched out of a single piece of metal. A flange 6 is provided around the edge of the cup, the front end of the cup being open-ended, as shown at 7. This front end is 55 closed by a sound-producing device, here

shown as a vibratile diaphragm 8, whose edge 9 is connected between the flange 6 and a flange 10 upon the casing front 11. The casing front 11 is provided with an opening 12 for the egress of sound waves. 60 A resonator 13 may be mounted in this opening, as illustrated in the drawing.

As will be seen, the central portion of the diaphragm is free to vibrate when the diaphragm is agitated. An anvil 14 is mounted 65 in the diaphragm, preferably at the center thereof. This anvil is shown as a screw passing through the diaphragm. The diaphragm is provided with an opening 15 and a screw or anvil bearing 16 is mounted in 70 this opening. In the form shown, this bearing consists of a member 17 which is provided with a flange 18 abutting against the inner side of the diaphragm and a sleeve 19 which fits over the main portion of the member 17 upon the front of the diaphragm. A lock nut 20 is provided for locking the 75 parts in position.

Means are provided for striking the end 14 of the anvil and causing the actuation of 80 the diaphragm. This is here shown as a toothed wheel 21 provided with a plurality of teeth 22, preferably being shaped like the teeth of a saw. The wheel 21 is mounted to rotate in the frame. Here it is fastened to 85 a shaft 23 which is mounted in bearings 24 in the frame in which bearings it rotates. I prefer to mount the wheel rigidly upon the shaft, so that it rotates with the shaft. A plurality of teeth 25 are connected to the 90 wheel 21 and rotate therewith. Here they are mounted upon the shaft in the shape of a spur wheel 26.

A manually operable member, here shown 95 as a plunger 30 is mounted to operate in the frame. This plunger or rack is provided with a plurality of teeth 31, preferably cut directly in the rack and upon one of the edges thereof. At 32 is shown a guide for the rack, which may constitute a part of 100 the frame and which is provided with a pair of ears 34 and 35. These ears are provided with longitudinal slot bearings 40, which are best made perpendicular to the axis of rotation of the shaft 23, in which a spur 105 axle 41 is mounted. A spur gear 42 is mounted upon the spur axle 41. The spur gear 42 is provided with a plurality of teeth 43 adapted to coöperate with the teeth 25. These parts serve as a one-way power trans- 110

mission clutch between the rack and the teeth 25. Means are provided for returning the rack 30 to normal, here shown as a coil spring 50, which extends into a bore 51 in the rack. An anchor block 52 connected to the frame by a screw 53 fits in the bottom of the rack casing 32. A spring guide pin is shown at 100.

Means are provided for giving considerable inertia to the wheel 21, here shown as a weight 55 connected to the wheel 21 in any suitable manner, such as by bolts 56. I may also provide a spacer 57 concentric with the shaft 23 and spacing the member 15 55 from the frame.

I may provide means to quicken the engagement between the gears 42 and 26, here shown as a spring 60. In the form shown, a bow spring has been employed, which 20 bears against two shafts 23 and 40. This spring is intended to insure the engagement of these gears at the proper time, should the horn be operated up-side-down, or set in some unusual position. Hand engageable 25 means, shown at 70, is connected to the rack, through which the same is operated.

The operation of the device is as follows: Pressure is applied, for example, by the hand to the member 70 and the rack is forced 30 downwardly sliding in the casing 32 and compressing the spring 50. The teeth 31 upon the rack force the gear 42 downwardly until its teeth mesh with the teeth 25 of the gear 26. As the rack descends both gears 35 will be rotated, together with the shaft 23 and the cam wheel 21. As the teeth 22 of the cam wheel 21 strike the anvil 14, the diaphragm 8 will be caused to vibrate and the signal produced. The wheel 21 once 40 having been started will continue to rotate after the pressure upon 70 has ceased or been removed, the momentum of the member 55 causing the wheel 21, the shaft 23 and the wheel 26 to rotate, forcing the shaft 45 41 upwardly into the slot 40, the wheel 42 being carried upwardly therewith. When the pressure has been released from the member 70, the spring 50 will cause the rack to return to the position shown in Fig. 1, the 50 wheel 42 being in the position shown in Fig. 3 and not interfering with the continued rotation of the wheel 21 and the operation of the diaphragm.

I have shown this particular embodiment 55 of my invention and the details employed therein, not that I wish to be limited thereto, but for the purpose of better describing the invention, it being apparent to those skilled in the art that numerous and extensive departures may be made from both 60 the form and details illustrated in the drawing, without departing from the spirit of the invention.

I claim:

65 1. In an automobile horn, the combina-

tion of a frame, a vibratile sonorous diaphragm mounted in said frame, a shaft in said frame, a cam wheel mounted on said shaft, mechanical means through which the cam wheel operates the diaphragm when rotated, a plurality of gear teeth associated with said cam wheel and adapted to rotate therewith, a rack mounted to reciprocate in said frame, said rack being provided with a plurality of teeth, a spur wheel having 70 teeth meshing with the teeth on the rack and adapted to mesh with the teeth associated with the cam wheel and means to slidably mount said spur wheel in said frame.

2. In an automobile horn, the combination 80 of a frame, a vibratile diaphragm in the frame, a toothed wheel rotatably mounted in the frame, mechanical means through which the toothed wheel operates the diaphragm, a toothed gear wheel connected 85 with the toothed wheel and adapted to rotate therewith, a rack in the frame and a second toothed gear wheel slidably mounted in the frame between the rack and first gear wheel, said second gear wheel transmitting 90 power from the rack to the first gear wheel when the rack is moved in one direction.

3. In an automobile horn, the combination 95 of a frame, a vibratile diaphragm in the frame, a toothed wheel rotatably mounted in the frame for causing the actuation of the diaphragm, a plurality of gear teeth connected to the toothed wheel and rotatable therewith, a plunger in the frame and a slidably mounted gear wheel between said gear teeth and said plunger, adapted to cause the actuation of the toothed wheel when the plunger is moved in one direction.

4. In an automobile horn, the combination 105 of a frame, a diaphragm in the frame, a toothed wheel rotatably mounted in the frame for causing the actuation of the diaphragm, a plunger in the frame and means including a gear wheel caused to slide when the plunger is operated to transmit power 110 from the plunger to the toothed wheel.

5. In an automobile horn, the combination 115 of a frame, a vibratile diaphragm in the frame, a toothed wheel rotatably mounted in said frame, mechanical means through which the toothed wheel operates the diaphragm, gear teeth rotatable with said wheel, a member in said frame provided with slot bearings, a toothed plunger in said frame, a spur axle in said slot bearings, and 120 a spur gear on said axle between said plunger and said toothed wheel provided with teeth adapted to engage the teeth on the plunger and the gear teeth rotatable with the wheel.

6. In an automobile horn, the combination 125 of a frame, a vibratile diaphragm in the frame, an anvil in the diaphragm, a toothed wheel rotatably mounted in the frame and adapted when rotated to cause the actuation 130

of the diaphragm through the anvil, a plurality of gear teeth connected to the toothed wheel and adapted to rotate therewith, a member provided with slot bearings in said frame, a spur axle in said slot bearings, a rack mounted in the frame and adapted to be reciprocated therein and a spur gear mounted upon said spur axle having teeth meshing with the teeth on the rack and adapted when the rack is depressed to mesh with the gear teeth connected to the toothed wheel.

7. In an automobile horn, the combination of a frame, a diaphragm in the frame, an anvil in the diaphragm, a toothed wheel rotatably mounted in the frame adapted to cause the actuation of the diaphragm when the wheel is rotated, a plurality of gear teeth associated with the toothed wheel, a member in the frame provided with slot bearings, a rack mounted to reciprocate in said frame, said slots being substantially parallel to the line of movement of said rack, a spur axle in said slot bearings, and a toothed gear wheel on said axle having teeth meshing with the teeth on the rack and adapted to mesh with the gear teeth connected to the toothed wheel and cause the rotation of the toothed wheel when the rack is moved in one direction.

8. In an automobile horn, the combination of a frame, a vibratile sonorous diaphragm in said frame, means to connect the periphery of the diaphragm to said frame leaving the central part of the diaphragm free to vibrate, an anvil in the central part of the diaphragm, shaft bearings in said frame, a shaft rotatably mounted in said bearings, a heavy rotatable toothed wheel connected on said shaft and rotatable therewith, the teeth on the wheel adapted to strike said anvil and cause the diaphragm to vibrate when the wheel is rotated, a spur gear wheel con-

nected to said shaft and rotatable therewith, a rack mounted to reciprocate in said frame, a member in said frame provided with slot bearings, said slots being substantially parallel to the line of movement of said rack, a spur shaft loosely mounted in said slot bearings, a spur wheel on said spur shaft for transmitting power from said rack to said gear wheel on the shaft when the rack is depressed, and means to restore said rack to normal when released.

9. In an automobile horn, the combination of a frame, a vibratile diaphragm connected at its periphery to said frame, an anvil in the diaphragm, a toothed wheel rotatably mounted in said frame, a plurality of gear teeth connected to said wheel and rotatable therewith, a plunger guide in said frame provided with a pair of slot bearings, a plunger adapted to reciprocate in said guide, a spur wheel having teeth adapted to be engaged by said plurality of gear teeth and said plunger, said spur wheel loosely mounted in said slot bearings.

10. In an automobile horn, the combination of a frame, a diaphragm connected at its periphery to said frame, an anvil in the diaphragm, a heavy toothed wheel mounted in the frame and adapted when rotated to cause the actuation of the diaphragm through the anvil, a plurality of gear teeth connected to and rotatable with the toothed wheel, a rack guide in the frame, ears on said guide provided with slot bearings, a rack in said guide and a spur gear wheel loosely mounted in said slot bearings, said gear wheel being provided with teeth adapted to engage the teeth on the rack and the gear teeth connected to the toothed wheel.

In witness whereof I have hereunto signed my name this 18th day of March, 1916.

CHARLES SIMEK.
